UNITED STATES PATENT OFFICE.

VICTOR E. CAMPBELL, OF PORTLAND, OREGON, ASSIGNOR TO CAMPBELL'S AUTOMATIC SAFETY GAS BURNER CO., OF PORTLAND, OREGON.

AUTOMATIC CUT-OFF FOR LIQUID AND GASEOUS FUEL BURNERS

No. 891,761.

Specification of Letters Patent.

Patented June 23, 1908.

Application filed January 17, 1908. Serial No. 411,330.

To all whom it may concern:

Be it known that I, VICTOR E. CAMPBELL, a citizen of the United States, residing at Portland, in the county of Multnomah and 5 State of Oregon, have invented a new and useful Automatic Cut-Off for Liquid and Gaseous Fuel Burners, of which the following is a specification.

This invention relates to liquid and gaseous fuel burners, and has for its principal object to provide means for automatically cutting off the flow of fuel in case the fire is extinguished, or in the event of failure to ignite the gas or gasolene after the valve has 15 been moved to open position.

A further object of the invention is to provide a novel form of thermostatically controlled valve in which the valve is closed by a motor mechanism, the necessary energy for 20 effecting the closing movement being stored as the valve is moved to open position.

A still further object of the invention is to construct a device of this type in which on the opening movement of the valve, energy is 25 stored and is held under control until the valve is to be closed.

With these and other objects in view, as will more fully hereinafter appear, the invention consists in certain novel features of construction and arrangement of parts, herein-after fully described, illustrated in the accompanying drawings, and particularly pointed out in the appended claims, it being understood that various changes in the form, 30 proportions, size and minor details of the structure may be made without departing from the spirit or sacrificing any of the advantages of the invention.

In the accompanying drawings:—Figure 1 40 is a sectional elevation of a gasolene burner provided with a valve closing mechanism constructed in accordance with the invention. Fig. 2 is a detail sectional view through a portion of the motor mechanism. Fig. 3 is a transverse sectional view with the cam disk and its hub in elevation, showing the mechanism for holding the motor spring wound, the parts being illustrated in the position assumed when the valve is closed. Fig. 4 is a similar view, showing the position 45 of the parts with the valve open. Fig. 5 is a sectional plan view through the burner head. Fig. 6 is a view corresponding to Fig. 1 illustrating a modified construction. Fig. 7 is a 50 detail sectional view of a portion of the mech-

anism shown in Fig. 6. Fig. 8 is a transverse sectional view on the line 8—8 of Fig. 6. Fig. 9 is a similar view on the line 9—9 of Fig. 6. Fig. 10 is a transverse section on the line 10—10 of Fig. 6. Figs. 11 and 12 are detail 60 perspective views of the releasing lever which receives motion from the thermostat element.

Similar numerals of reference are employed to indicate corresponding parts throughout 65 the several figures of the drawings.

The present invention may be used in connection with any type of fluid burner, and, in the present instance, is shown as applied to the burner 10 of an ordinary form of gasolene 70 stove. The burner is provided with a supply or stand pipe 11 through which the gasolene passes to the burner head, and is there vaporized, the vapor passing through a pipe 12, and being under the control of a main valve 75 13. The burner is, also, provided with an ordinary form of needle valve 14, which controls the flow of gas through the burner orifice or passes through a mixing tube 15.

The valve 13 is carried by or forms a part 80 of a rod 16 and the outer end of the rod is provided with a handle 17 of the ordinary type, the turning of this handle serving to open and close the valve, so that the device may be manually operated in precisely the 85 same manner as any ordinary form of gasolene burner.

Mounted on the valve rod is a post 20, the upper portion of which is grooved or slotted and to the rear face of the post is secured a 90 coupling nipple 22. The nipple is internally threaded for the reception of a thermostat tube 23 that preferably is formed of brass. This tube extends through a sleeve 24 that is carried by a block 25, the latter being secured 95 within the burner head by screws or similar fastenings 26.

The inner end of the tube is closed, and through said tube extends a rod or wire 28 which in practice is formed of steel or iron, 100 the tube and rod being formed of metals having different co-efficients of expansion, so that the rod may be moved in the direction of its length when subjected to different temperatures. The inner end of the rod is 105 bent downward and passes through a suitable opening formed near the inner end of the tube, and the rod is preferably brazed or otherwise permanently secured at its inner end.

It is found in practice that the entire rod need not be formed of steel or iron, inasmuch as the necessary movement may be secured by a rod of much shorter length. The 5 inner end only of the rod, therefore, is formed of steel, while the outer portion is of brass or of the same metal as that of which the tube is constructed.

Secured to the opposite sides of the post 20 10 are two disks 32 and 33, and to the outer of these disks is secured an approximately hemi-spherical casing 34, which conceals the motor mechanism, the central portion of the casing being provided with an opening for 15 the passage of the valve carrying stem 16. Mounted loosely on the valve stem 16 is a cylindrical hub 35 of a cam disk 36, and from the outer end of the hub projects a pin 37 which is connected to a pin 38 on the stem 16 20 by a helical torsion spring 38', the connections being so arranged that when the stem is turned in the direction indicated by the arrow, Fig. 3, for the purpose of moving the valve to open position, the movement of the 25 stem will be transmitted to the hub and cam through the spring 38'. The hub 35 serves, also, as a spring winding barrel, and is provided with a hook 40 of the usual type for connection to the inner end of a spiral spring 30 41, the outer end of said spring being secured to a post 42 that projects from the disk 33, and as the stem is turned in the direction indicated by the arrow in Fig. 3, the spring will be wound and placed under stress. 35 Pivoted on a pin 43 that projects from the disk 33 is a lever 44 that is bent into approximately semi-circular form, and at the pivot end of said lever are two oppositely facing tongues 45 and 46, the tongue 45 being 40 arranged to enter a recess 47 formed in the cam disk 36 when the parts assume the position shown in Fig. 4, and the tongue 46 being arranged to engage a shoulder 48 that is formed on the periphery of the cam disk 45 when the parts assume the position shown in Fig. 3, this latter being the normal position when the valve is closed.

The upper end of the lever is slightly curved to form a locking shoulder 50 that is 50 arranged to be engaged by an anti-friction roller 51 carried by a pawl 52 that is pivoted on a pin 53 carried by the disk 33. This pawl is under the control of the thermostat and is held in elevated idle position when the 55 stove is cold.

Arranged within the slotted portion of the post 20 is a lever 62 which preferably is formed of stamped sheet metal, and the upper portion of this lever is provided with a 60 pair of parallel slots, the metal at the slit portion being bent in opposite directions in order to form an opening for the passage of a short shaft or pin 63 on which said lever is pivotally mounted. The lower end of this 65 lever engages with a bell crank lever 64 of

the construction best shown in Fig. 12. This lever is formed of stamped sheet metal and is provided with a pair of pivot ears 65 for the reception of a transversely extending pivot pin 66. The approximately vertical 70 and shorter arm of the bell crank lever is provided with a pair of guard ears 67 in order to prevent any lateral play of the lower end of the lever 62. The approximately vertical and longer arm of the lever 64 extends outward through an opening formed in the disk 33 and normally rests in a position under the pawl 52.

The upper end of the lever 62 is engaged by a thermostat rod 28, and as the latter is 80 moved outward away from the burner, this movement will be transmitted from the lever 62 to the bell crank lever 64, and the latter in turn will operate the pawl 52, raising said pawl from engagement with the shoulder 50 85 of the locking lever 44 when the parts are in the position shown in Fig. 4, so that the motor spring may be allowed to unwind for the purpose of turning the cam disk, and its hub, back to the position shown in Fig. 3, and 90 thus effect closing of the valve.

When the valve stem is turned to open position, the cam disk 36 will be turned around to the position shown in Fig. 4, and the tongue 45 will ride into the recess 47 of the cam, thereby moving the upper end of the lever 44 inward to the position shown in Fig. 4, and when the burner is heated and the thermostat operated, the lever 64 will descend to a sufficient extent to allow the pawl 52 to move to the locking position, as indicated in Fig. 4. The parts remain in this position until the burner becomes cold through extinguishing the flame, and then the pawl 52 is raised in order to allow the spring to expand and turn 100 the valve stem to the closed position, as previously described. 105

As the hub 35 is turned in closing the valve, the valve closing movement is assisted through the spring 38 and the adjustment of 110 the parts is such that the valve is brought to its seat by the main spring 41 before the stem 16 has completed its rotation, thereby closing the valve firmly, but at the same time the spring 38 operates to prevent jamming of the 115 valve and damage to the contacting portions of the valve and its seat.

The apparatus as described, operates to close the controlling valve very quickly, but, in some cases, it may be desired to slightly 120 retard the valve closing operation, so that the actuating spring will operate more slowly in cutting off the flow of fluid to the burner, and for this purpose the construction shown in Figs. 6 to 10, inclusive, may be 125 employed.

Mounted loosely on the valve rod 16' is a sleeve 55 from which extends a pin 56 that is arranged parallel with the valve rod, and projecting from the latter is a pin 57 which 130

engages with the pin 56 and revolves the sleeve each time the valve is moved to open position. Mounted on the sleeve is a strong spiral spring 41', the inner end of which is secured to the sleeve, while the outer end of the spring is secured to a pin 42' that projects from the innermost disk 32, this pin extending through and serving as a support for a guard disk 60 which, in connection with a smaller guard disk 61, serves to protect the sleeve, this construction being common to both devices.

The sleeve carries a large gear wheel 62' which meshes with a pinion 63' on a shaft 64'. The shaft 64' carries a fixed ratchet wheel 65' with which engages a pawl 66' of a loose wheel 67' on the shaft. The wheel 67' is connected through a train of gearing to an escapement wheel arbor 68', carrying an escapement 69 with which engages an anchor escapement 70 that is provided with a weight 71 in order to retard its operation. The anchor is mounted in suitable bearings, one of which is formed of a suitable bridge 72 secured to the outer disk 33. Bearing on the escapement wheel is a locking member 52' that is held down in locked position by a spring 74, and the locking member is under the control of the lever 64 which is actuated by the thermostat in the same manner as in the construction shown in Figs. 1 and 2.

The apparatus may be employed to advantage in connection with any form of burner and with any fuel, the type of controlling device being modified to suit the particular fuel being used:

I claim:—

1. The combination with a burner head; of a controlling valve arranged below the burner head, a revoluble rod carrying the valve, a post mounted on the rod, a thermostat extending from the burner to the post, a motor mechanism supported by the post and connected to the valve rod, a motor locking device, and means carried by the post for connecting the thermostat to said locking device.

2. The combination with a burner head; of a valve arranged below the burner head, a post mounted upon the valve rod, a spring motor supported by the post, means for transmitting movement from the rod to the spring and placing the latter under stress when the valve is moved to open position, a motor locking device, and a thermostat connected to said locking device, the thermostat extending from the burner head to the post.

3. The combination with a burner head and a controlling valve, of a post mounted on the valve rod, a spring motor supported by said post, means for connecting the motor spring to the rod to store energy in the spring when the valve is moved to open position, a motor locking device, a thermostat extending from the burner head to the post, and a

pair of levers mounted in the post and arranged to transmit movement from the thermostat to the locking device.

4. The combination with a burner head and a controlling valve, of a rod carrying the valve, said rod being free to be moved to open and closed positions by hand, a post carried by the rod, the upper portion of the post being hollow, a spring motor, the spring being placed under stress during the opening movement of the valve, a motor locking device, a pair of levers arranged in the hollow portion of the post, the lowermost lever being connected to the locking device, and a thermostat extending from the burner head to the post and arranged to transmit movement to the upper lever.

5. The combination with a burner, of a controlling valve, a revoluble valve rod, a motor spring arranged to be placed under stress when the rod is turned to move the valve to open position, a motor locking device, a thermostat for moving the locking device to release position, and a yieldable connection between the motor and the rod to prevent the exercise of undue force on the rod in seating the valve.

6. The combination with a burner, of a fuel controlling valve, a rod for operating the valve, a hub mounted loosely on the rod, a torsion spring connecting the hub and rod, a motor spring extending between the hub and a fixed point, said motor being placed under stress when the rod is turned in moving the valve to open position, means for locking the motor spring, and a thermostat for moving the locking device to release position.

7. In combination, a burner, a fuel controlling valve therefor, a rod connected to the valve, the hub having a yieldable connection with the rod, a cam disk carried by the rod and provided with a locking shoulder and a locking notch, a motor spring extending between the hub and a fixed point, said spring being placed under stress when the rod is turned in moving the valve to open position, a cam disk engaging lever having a pair of oppositely directed tongues, one of which is arranged to enter the notch when the spring is wound, and the other of which is arranged to engage the locking shoulder of the disk to limit unwinding movement of the spring, a pawl arranged to engage said lever, and a thermostat for moving said pawl to release position.

8. The combination with a liquid fuel burner, of a fluid controlling valve therefor, a rod connected to the valve, a hub having a yieldable connection with the rod, a cam disk carried by the hub and provided with a locking notch and a locking shoulder, a pivoted lever having a pair of oppositely directed tongues; one arranged to enter the notch and the other to engage the shoulder of the disk, a pivotally mounted pawl, a roller carried

thereby and arranged to engage the lever, and a thermostat for moving said pawl to release position.

9. The combination with a burner including a burner head and controlling valve, of a revoluble valve carrying rod, a hollow post supported by the rod and provided with a projecting nipple, a spring motor mechanism arranged to be placed under stress by the turning of the rod during movement of the valve to open position, a locking device for the motor, a tube extending from the nipple to the burner head, a rod extending through the tube, the rod and tube being formed of metals having different coefficients of expansion, and means within the post for transmitting movement from the end of the rod to the locking devices.

10. The combination with a burner including a burner head and controlling valve of a revoluble valve carrying rod, a hollow post supported by the rod, a spring motor mechanism by which the spring is placed under stress during the turning of the rod to open the valve, a motor locking device, a thermostat extending from the burner head to the post, a bell crank lever mounted in the lower portion of the post and having its approximately horizontal arm connected to the locking device, and a second lever also arranged within the post, the upper end of said second lever being engaged by the thermostat and its lower end engaging said bell crank lever.

11. In combination a valve, a motor device in which potential energy is stored by the movement of the valve to open position, an elastic connection between the motor device and the valve and disposed to be placed under stress by the movement of the valve to open position and to be liberated upon the completion of such movement, means for

locking the motor device to prevent its operating to return the valve to closed position, and a thermostat for releasing said locking device.

12. In combination a valve, a motor in which the potential energy is stored by the movement of the valve to open position, and an elastic connection between the motor and valve and disposed to be placed under stress by the movement of the valve to open position and to be liberated upon the completion of such movement.

13. The combination with a burner head and a controlling valve; of a spring motor, an elastic connection between the motor and the valve and disposed to be placed under stress by the movement of the valve to open position and to be liberated upon the completion of such movement, a motor locking device, a thermostat extending into the burner head, and means actuated by the thermostat for shifting the motor locking device out of engaging position.

14. The combination with a burner head and a controlling valve; of a motor for actuating the valve, a cam disk revoluble with the motor, a cam engaging lever for holding the motor against rotation in one direction, a pawl cooperating therewith, a bell crank lever mounted adjacent and disposed to lift the pawl, a thermostat extending into and beyond the burner head, and a lever operated by the thermostat for actuating the bell-crank lever.

In testimony that I claim the foregoing as my own, I have hereto affixed my signature in the presence of two witnesses.

VICTOR E. CAMPBELL.
